HER ATTORNEY.

UNITED STATES PATENT OFFICE.

RACHEL COOPerman, OF CHICAGO, ILLINOIS.

TIE.

1,325,001.

Specification of Letters Patent.

Patented Dec. 16, 1919.

Application filed January 11, 1919. Serial No. 270,618.

To all whom it may concern:

Be it known that I, RACHEL COOPerman, a subject of the King of Roumania, and a resident of the city of Chicago, county of Cook, and State of Illinois, have invented certain new and useful Improvements in Ties, of which the following is a specification.

My invention relates in general to improvements in ties of the type which are provided with means for attaching the same to the collar when in use.

More specifically one of the objects of the invention is the production of a tie fastener which will be of durable and economical construction and efficient in use.

Other objects will appear hereinafter.

The invention consists in the features of novelty in substantially the combination and arrangement of parts hereinafter described and claimed.

The invention will be best understood by reference to the accompanying drawings forming a part of this specification, and in which,

Figure 1, is a perspective view of a conventional form of collar to which is applied a tie embodying the invention,

Fig. 2, a horizontal section through the front portion of the collar showing the application thereto of the tie,

Fig. 3, a central vertical section of the construction seen in Fig. 2, and

Fig. 4, a perspective view of the tie fastener.

The preferred form of construction, as illustrated in the drawings, embodies a bow tie 5 of conventional design, the same being embraced medially of its ends by a band 6.

Arranged at the back of the tie is a clasp or fastener for securing the same to a collar. This clasp or fastener embodies a pair of elongated superposed spring metal members 7 and 8 which are of bowed formation, one of which is preferably more resilient than the other, the ends thereof forming coöperating jaws adapted to embrace the adjacent front edges of an ordinary collar 9 in order to secure the tie thereto, as clearly seen in Fig. 2.

The parts 7 and 8 of the fastener are united together at their centers by means of a pair of ears 10 formed at the upper and lower edges of the member 8, and are bent back into engagement with recesses 11 formed in the member 7. With this ar-

rangement it will be seen that said members 7 and 8 will be rigidly connected together, the same being positively held against any relative shifting movement.

The fastener thus formed is secured to the tie by means of stitching 12, which is adapted to embrace the fastener at the points of location of the ears 10. Formed on the upper and the lower edge of member 8 at opposite sides of the ears 10 are spaced projections 13, which engage with the stitching 12 to securely hold the fastener against any relative shifting movement, it being clear that, with the construction set forth, recesses are formed adjacent opposite edges of the fastener between the projections 13 directly over the flanged ears 10, and at the center of the fastener, which recesses will serve to securely hold the stitching and thus prevent any relative shifting of the fastener. Moreover, the projections 13 engage with adjacent portions of the tie to further aid in holding the fastener in proper relation with the tie.

The construction set forth is extremely simple and permits of application of the fastener to the tie with great expedition.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. The combination with a tie, of a holder therefor embodying an elongated member arranged at the back of the tie; means embracing said member for securing the same to said tie; and a pair of spaced projections at the upper and lower edges of said member between which said securing means engages for confining said securing means centrally of the holder.

2. The combination with a tie, of a holder therefor embodying an elongated member arranged at the back of the tie; stitching embracing said member for securing the same to the tie; and a pair of spaced projections at the upper and lower edges of said member between which said stitching

engages for confining said stitching centrally of the holder.

3. The combination with a tie, of a holder therefor embodying a pair of elongated superposed members arranged at the back of the tie; a pair of ears on one of said members embracing the other of said members for securing the parts together; means embracing said members at the points of location of said ears for securing the same to the tie; and projections on one of said members at opposite sides of said ears engaging said securing means for confining the securing means centrally of the holder.
4. A necktie fastener embodying a pair of elongated superposed members shaped to form diverging extremities, one of said members being more resilient than the other member, ears formed on the opposite edges of one of the members intermediate its ends, said ears being flanged over the respective adjacent edges of the other member for securing the members together, and spaced projections formed on opposite edges of one of the members adjacent the sides of the respective ears, the said projections extending

beyond the lateral edges of both of the said members.

5. A necktie fastener embodying a pair of elongated superposed members shaped to form diverging extremities, one of said members being more resilient than the other member, ears formed on the opposite edges of one of the members intermediate its ends, said ears being flanged over the respective adjacent edges of the other member for securing the members together, and spaced projections formed on opposite edges of one of the members adjacent the sides of the respective ears, the said projections extending beyond the lateral edges of both of the said members, the bent portion of the ears which pass over the edges of the other member defining the bottom of the spaces formed between the respective adjacent projections.

In testimony whereof I have signed my name to this specification in the presence of two subscribing witnesses.

RACHEL COOPerman.
